UNITED STATES PATENT OFFICE.

IDA W. PENNEY, OF BUFFALO, NEW YORK.

TAPE-NEEDLE.

SPECIFICATION forming part of Letters Patent No. 618,365, dated January 24, 1899.

Application filed May 2, 1898. Serial No. 679,479. (No model.)

To all whom it may concern:

Be it known that I, IDA W. PENNEY, a citizen of the United States, residing at Buffalo, in the county of Erie and State of New York, have invented a new and useful Improvement, 5 in Ribbon-Needles, otherwise known as "Tape-Needles" or "Bodkins," such as are used in beading, insertion, &c., of which the following is a specification.

The object of my improvement is to provide an eye for such a needle that will permit the use of ribbons of different widths in the same needle, which will allow a ribbon wider than the needle itself to be used without making it necessary to double or twist the ribbon in threading the same, that will hold the ribbons, whether the same be of the narrowest width or of a width equal to the length of the slit constituting the eye, preventing them from twisting or turning, and which makes it possible to thread the needle very easily, whether the ribbon be narrow or wide. I attain these objects by means of the slit at the top of the needle constituting the eye (illustrated in the accompanying drawings) and formed by a narrow slit starting from a point near the outer edge of the needle and proceeding away from the point of the needle in a curved line to a point opposite the point of 15 the needle, and thence toward the point of the needle and in a curved line to a point substantially opposite the place of beginning, and thereby forming a tongue out of that portion of the needle included between the 20 legs of the narrow slit. Owing to the peculiar formation of the eye, the ribbon, of whatever

one of the intermediate sizes within the limits hereinbefore mentioned, is held in the needle in such manner as to prevent its wrinkling or twisting by means of that portion of 40 the needle between the legs of the slit forming a tongue, which said portion of the needle is marked *x* in the accompanying drawings and, as hereinbefore stated, is adapted equally as well to all ribbons of the different 45 sizes of widths described in the foregoing part of this specification. The needle, being perfectly plain, passes through without catching in the beading, and the manner in which the ribbon is held in this slit or eye admits 50 of the ribbon passing through without catching its ends in the beading—a feature which is not possessed by any other ribbon-needle or bodkin heretofore used and which will allow a ribbon wider than the needle itself to be 55 used—*e. g.*, the ribbon-needle which holds the ribbon by means of a clamp.

Figure 1 in the accompanying drawings represents the needle. Fig. 2 is an enlarged view of the slit at the top of the needle, forming a 60 tongue and constituting the eye.

I claim as my invention and desire to secure by Letters Patent—

A tape-needle of flat metal having an eye comprising a curvilinear slit starting near one 65 edge of the needle and proceeding in a curved course to an opposite point near the other edge, forming the tongue *X*, as set forth.

IDA W. PENNEY.
